2,687,124

PREHEAT APPARATUS FOR SMALL ENGINES

Franz J. Neugebauer, Schenectady, N. Y., and
Hans O. Berkner, Dayton, Ohio, assignors to
the United States of America as represented
by the Secretary of the Air Force

Application May 20, 1952, Serial No. 288,994

8 Claims. (Cl. 123—142.5)

(Granted under Title 35, U. S. Code (1952),
sec. 266)

1

The invention described herein may be manufactured and used by or for the Government for governmental purposes without the payment of any royalty thereon.

This invention relates to a device for pre-heating small engines during cold temperatures without resorting to an external power source.

In the subject invention a stack and burner is utilized in combination with an engine, the burner creating a very high temperature gas in the stack. This high temperature is necessary for generating a substantial draft in the stack, but this high temperature is too great for the equipment to be preheated to withstand. To overcome this difficulty, the subject invention incorporates heat exchangers for conducting heat from the stack to the engine elements to be heated. The amount of heat conducted by the heat exchangers from the stack depends upon the length, cross-sectional area, and the heat conductivity of the material of which the heat exchangers are made. The material and dimensions for designing the heat exchangers can be selected within a wide range to conduct a heat temperature suitable for the engine elements in spite of the high temperature in the stack.

Therefore, an object of the invention is to provide a simple preheating device for engines, which device does not depend on an external source for power.

A further object of this invention is to provide means for conducting heat from a high temperature source to the components of an engine at a satisfactory operating temperature.

These and other objects will become more apparent from the accompanying drawings and specifications wherein similar parts have like numbers and wherein:

Figure 1 shows the arrangement of a single cylinder gasoline engine in combination with a stack burner and heat exchanger.

Figures 2 and 3 are views showing the design of heat exchangers used in the device of Figure 1.

Figure 4 shows a device for preheating the carburetor air.

Figures 5 and 6 show the subject invention adapted to a two-cylinder engine.

Figures 7 and 8 show a method of heating an oil pan.

Referring to Figures 1-3 a single cylinder engine is generally designated as 10 with a vertical stack 12 open at both ends mounted along side thereof. The burner arrangement 14 is located within the lower portion of the stack 12. The stack 12 is provided with openings 15 for the

2

entrance of air to the burner. The burner 14 may be automatically operated to turn it on and off by an automatic means such as a spark plug and magneto arrangement 13. Immediately above the burner 14 is mounted a heat exchanger 16 for heating the bearings and the piston of the engine by heat convection and radiation. The heat exchanger 16 is in the form of an L but may be any other desired shape as the design requirements may require. The center portion 19 of the L is solid and may be of any convenient cross sectional area depending on the rate of heat conduction desired. From each end of the solid portion 19 extend the elements or fins 17, one end extending into the stack 12 and the other end above the oil level in the crankcase 18. An additional heat exchanger 20 is located at the carburetor 22 of the engine. One end of this heat exchanger enters the carburetor and the other end extends into the stack 12. A manifold 23 surrounds the stack 12 and is connected to the carburetor 22 for heating the air entering into the carburetor.

The temperature above the burner may be over 1500° F. which is too great for the engine and oil pan to withstand, their maximum being about 400° F. to 500° F. The material and dimensions of the heat exchangers must be selected so that during the heating time, the temperature of the

heat exchangers do not exceed the temperature limit of the lubricant or engine components. If the amount of heat conducted is required to be high, then the material of the heat exchangers should be of copper and the solid part between the fins should be of a large cross-sectional area and of short length. In order to cut down the rate of heat conduction the heat exchangers may be made of aluminum inside the oil pan and of copper or steel inside the stack and of a larger length center portion 19 having a smaller cross-sectional area and by including a circumferential groove 21 in the solid center portion. The burner is a multi-fuel burner which is able to operate on gasoline as well as kerosene, jet fuel or diesel fuel.

In operation the burner 14 may be ignited either automatically or by hand, preferably automatically by a spark plug and magneto arrangement. The burner will generate a very high temperature in order to create a large draft in the stack in an upward direction resulting in a thermosiphon. The heat will be conducted from the stack to the oil in the crankcase and carburetor by the heat exchangers. The material and dimensions of the heat exchangers 16 and 20 are

50
55

such as to conduct only a predetermined heat to the engine elements. When the carburetor and the oil in the crankcase reach a predetermined temperature value the burner can be automatically turned off and the engine can then be started.

Referring to Fig. 4 the carburetor 22 is so disposed as to open into the stack 12 at 21 so that it might be possible to preheat the carburetor air during the operation of the engine during which time the burner is not in operation. The exhaust pipe 24 extends through the stack 12. Mounted on the exhaust pipe are fins 25 located within the stack for heating the air passing over the pipe. Butterfly valves 26 and 28 (Figure 1) are provided in the upper portion and lower portion of the stack respectively for controlling the air flow for different heating and operating conditions. An adjustable ring 30 (Figure 1) is adapted to cover the air holes 15, and also provides a means for controlling the air flow for different heat and operating conditions. Whereupon by adjusting the butterfly valves 26 and 28, and the ring 30, during operation of the engine, the air passing over the heated fins attached to the exhaust 24 will be heated and carried to the carburetor to obtain better performance of the carburetor during engine operation.

Referring to Figures 5 and 6 in which a two-cylinder diesel engine is shown, the heating gas from the burner 16 is guided along the oil pan 18 which in this embodiment contains the heat exchanger 32. The hot gas is led through hollow spaces 34 in the covers, along heating channels 36 in the crankcase, and along pipes 38 to the stack 40. The pipes 38 can be arranged close to the engine cylinder and to the fuel injection pump to heat them by convection and by radiation. Since the heating gas must pass through horizontal ducts, in this case, it might be difficult to start the stack from cold condition. For this reason a bypass 42 is provided to extend from the burner to the stack to generate an initial draft by guiding the small amount of hot gases immediately from the burner to the stack 40.

Figures 7 and 8 show another method of heating an oil pan in a crankcase. The oil pan is designated as 50 and is an aluminum casting having integral fins 52 and integral tubular mountings 53 therewith. The heat exchangers consist of one or more finned pipes 54 having central openings 55 and partitions 57 therein. The pipes are made of heat resistant steel which has a low heat conductivity factor. The circumference of the pipes is provided with grooves 56 to further decrease the rate of heat conduction.

In operation the heat passes through the openings 55 of the finned or fluted pipes 54, up through the partitions 57, to the oil pan 50 so as to heat the oil therein to the desired temperature.

By the several embodiments shown of the invention a simple and compact device for heating small engines is provided. The simple burner does not need an external source of power, such as a battery, for its operation, and furthermore does not merely rely on gasoline but is designed as a multifuel burner.

It is apparent that specific embodiments shown above have been given by way of illustration and not by way of limitation and that the structures above described are subject to wide variation and modification without departing from the scope or intent of the invention, all of which variations and modifications are to be considered as equivalents and be included within the scope of the present invention.

We claim:

1. In combination with an engine having an oil pan and carburetor, preheat equipment comprising a vertical stack connected adjacent to said engine, said stack being open at both ends for the passage of air therethrough, a burner located in the lower portion of said stack for heating the air and creating a thermo-siphon to move air in an upward direction, a first heat exchanger having one element of low heat conductivity material extending into said stack and another element of high heat conductivity extending into said oil pan, a second heat exchanger having one element of low heat conductivity material extending into said stack and another element of high heat conductivity connected to said carburetor, a third heat exchanger comprising a manifold surrounding the stack for heating the air entering into said carburetor, the elements of the first and second heat exchangers are connected together by solid central portions having reduced cross-sectional areas which may be varied to control the amount of heat conduction therethrough.

2. The combination as in claim 1, wherein, the elements of the first and second heat exchangers are comprised of fins at one end which extend into the path of the hot gases in said stack, and fins at the other end which contact the engine elements to be preheated.

3. The combination as in claim 1, wherein the elements of two of the said heat exchangers comprise fins at each end of the solid central portion, the one end extending into the stack being made of steel and the other end extending into said engine adjacent to the parts to be preheated being made of aluminum.

4. In combination with an engine having an oil pan and carburetor, preheating equipment comprising, a stack open at both ends connected adjacent to said engine and having a combustion chamber therein provided with air openings, and an adjustable ring covering said air openings regulating air flow therethrough, a multifuel burner in the lower portion of said stack, a finned heat exchanger in the path of the hot gases in said stack and in contact with said oil pan, the said heat exchanger having a groove therein for controlling the amount of heat conducted from the stack to said oil pan.

5. In combination with an engine having an oil pan and carburetor, preheating equipment comprising, a stack open at both ends connected adjacent to said engine and having a combustion chamber therein provided with air openings, and an adjustable ring covering said air openings regulating air flow therethrough, a multifuel burner in the lower portion of said stack, a finned heat exchanger in the path of the hot gases in said stack and in contact with said oil pan, the said heat exchanger provided with means for controlling the amount of heat conducted from the stack to said oil pan.

6. In combination with an engine and its components, preheating equipment comprising means adjacent to said engine for generating the source of heat, finned heat exchangers for conducting a controlled amount of heat to said components, said heat exchangers comprising fins at one end of low heat conductivity material contacting the source of heat and fins at the other end of high heat conductivity material contacting said components.

7. In combination with an engine and its components, preheating equipment comprising means

adjacent to said engine for generating a source of heat, finned heat exchangers for conducting a controlled amount of heat to said components, said heat exchangers comprising fins at both ends, and means for controlling the amount of heat applied to the fins at one end, for controlling the amount of heat conducted to the fins at the other end which are in contact with components of the engine.

8. In combination with an engine having an oil pan and carburetor, preheating equipment comprising means adjacent to said engine for generating a source of heat, finned heat exchangers for conducting a controlled amount of heat to said oil pan and carburetor, said heat exchangers comprising fins at each end of the heat exchanger, the amount of heat being controlled by the por-

tion between the fins having a predetermined cross-sectional area and length for conducting the amount of heat desired.
